PEGBOARD MOUNTED SUPPORT FOR SABRE SAWS, JIGSAWS, OR THE LIKE

Albert J. Enckler, North Olmsted, Ohio, assignor to
ABL Associates, Inc., Cleveland, Ohio

Filed Sept. 11, 1975, Ser. No. 602,528

Term of patent 14 years

Int. Cl. D6—04

U.S. Cl. D6—114

Fig. 1

Fig. 2

Fig. 3

FIG. 1 is a perspective view of a pegboard mounted support for sabre saws, jigsaws, or the like showing my new design;

FIG. 2 is a front elevational view thereof;

FIG. 3 is a side elevational view thereof.

I claim:

The ornamental design for a pegboard mounted support for sabre saws, jigsaws, or the like, as shown and described.
